(57) **CLAIM**

The ornamental design for a mobile phone, as shown and described.

DESCRIPTION

FIG. 1 is a perspective view of a mobile phone showing our new design in which the back cover has been closed in a condition that the display part has been bent backwards;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a perspective view thereof, showing the back cover in a closed position and the display portion unfolded;

FIG. 8 is a perspective view thereof, showing the back cover in an open position and the display portion bent backwards;

FIG. 9 is a front view of FIG. 8;

FIG. 10 is a rear view of FIG. 8;

FIG. 11 is a top plan view of FIG. 8;

FIG. 12 is a perspective view thereof, showing the back cover in an open position and the display portion unfolded;

FIG. 13 is a front view of FIG. 12;
